LOADER MACHINE

Joseph B. Kucera, Traer, Iowa

Application January 11, 1946, Serial No. 640,545

5 Claims. (Cl. 214—140)

1

This invention relates generally to loader machines and in particular to a loader attachment for a tractor adapted to handle dirt, manure, hay and the like.

An object of this invention is to provide an improved loader machine.

A further object of this invention is to provide a tractor loader attachment of a construction such that it can be easily removed from and assembled on a tractor by one man with a minimum of time and effort.

Another object of this invention is to provide a loader machine in which pivoted lifting arms, pivotally supported on a portable frame and having a scoop supported between their forward ends, are of a construction, such that the scoop, for a given length of the arms, is movable a greater distance forwardly of the frame to a dumping position.

Yet a further object of this invention is to provide a loader machine in which pivoted lifting arms are pivotally supported on the machine frame in a manner to have portions of the lifting arms counter balance a part of the load to be lifted.

A still further object of this invention is to provide a loader attachment for a tractor in which pivoted lifting arms, pivotally supported intermediate their ends, carry a scoop between their forward ends and are connected at their rear ends with tractor operated means adapted to pivotally move the arms to raise and lower the scoop.

Yet another object of this invention is to provide a loader attachment for a tractor which is of a simple and rugged construction, capable of being assembled on the tractor without interfering with the maneuverability of the tractor, with the full visibility of the tractor operator, or with the usual storage of the tractor, and efficient in operation to quickly load and unload a scoop with a minimum of attention and effort by the tractor operator.

A feature of this invention is found in the provision of a loader attachment for a tractor in which a pair of pivoted lifting arms are provided, intermediate their ends, with upright projections on which the arms are pivotally supported above the tractor rear axle. The front ends of the arms extend forwardly of the tractor and carry a scoop, while the rear ends of the arms are extended rearwardly of the tractor rear axle. Power operated means at the rear end of the tractor are connected with the rear ends of the arms to pivotally move the arms to raise and lower the scoop.

2

A further feature of this invention is found in the provision of a loader attachment for a tractor in which pivoted lifting arms are supported intermediate their ends on the tractor rear axle, so that the rear sections of the arms act to counter-balance a part of the load being lifted. Means for raising and lowering the arms are connected to the rear ends of the arms to fully utilize the leverage effect of the rear section relative to the pivotal support for the arms.

Further objects, features and advantages of this invention will become apparent from the following description when taken in connection with the accompanying drawings in which:

15 Fig. 1 is a side elevational view of a tractor with the loader attachment of this invention assembled thereon, with portions of the tractor being broken away and shown in section to more clearly show the construction of the attachment;

20 Fig. 2 is an enlarged sectional view taken on the line 2—2 in Fig. 1 showing the latch mechanism for the scoop;

Fig. 3 is a detail perspective view of a rock arm forming part of the means for raising and lowering the pivoted arms of the loader attachment;

25 Fig. 4 is a fragmentary rear perspective view of the tractor and attachment assembly shown in Fig. 1;

Fig. 5 is an enlarged sectional view taken on the line 5—5 in Fig. 4;

30 Fig. 6 is a fragmentary plan view of the rear end portion of the tractor and attachment assembly shown in Fig. 1;

Fig. 7 is a rear perspective view of the scoop showing the latch mechanism and the assembly of the scoop with the loader lifting arms;

Fig. 8 is a detail perspective view of a connecting member between the forward ends of the lifting arms;

40 Fig. 9 is a plan view of the assembly shown in Fig. 7;

Fig. 10 is illustrated similarly to Fig. 1 and shows a modified form of lifting means for the pivoted lifting arms;

45 Fig. 11 is a plan view of the lifting means shown in Fig. 10; and

Figs. 12, 13, and 14 are sectional views taken on the lines 12—12, 13—13, and 14—14, respectively, in Fig. 11.

50 With reference to the drawings the loader attachment of this invention is illustrated in Fig. 1 in assembly relation with a commercial type John Deere tractor, having a frame, indicated generally as 20, a rear axle structure 21 including a differential housing 22 and a rear power take-off shaft 23, rear wheels 24 and front steering wheel 25.

The attachment comprises a pair of pivoted lifting arms 27 and 27a (Figs. 1 and 6) arranged at opposite sides of the tractor and of a length such that their forward ends extend forwardly ahead of the tractor, and their rear ends project rearwardly behind the tractor. Since the arms 27 and 27a are of a like construction and similarly assembled with the tractor, only the construction and assembly of the arm 27 will be described in detail.

The arm 27 (Fig. 1) includes a main member 28 of a straight length and a pipe construction provided intermediate its ends with an upright plate member 29. A brace member 31, of a pipe construction, is welded or otherwise secured to the top side of the plate member 29 and has its opposite ends inclined downwardly from the top of the plate member 29 for junction with the ends of the main member 28. As shown in Fig. 4 the rear ends of the main member 28 and the brace member 31 are of a flat form and welded to a common plate member 32. The front ends of the members 28 and 31 (Figs. 7 and 9) are of a flat form and welded to a plate member 33 extended in a rearward direction longitudinally of and to the inside of the lifting arm 27.

The lifting arm 27 extends across the top of tractor rear axle 21 and is pivotally supported at a position spaced upwardly from the axle 21 by means including an upright U-shape member 34, having downwardly extended lugs 36 adapted to straddle the axle 21 (Figs. 1 and 6). The lugs 36 are secured to the axle by bolts 37. The arm 27, at the upright plate or projection 29, is received within the U-member 34 and pivotally supported on a pin or bolt member 38 carried in the legs of the U-member 34 and extended through an opening formed in the upright plate 29. It is seen, therefore, that the pivotal support 35 is spaced upwardly from the arm member 28.

Guide members 38 (Fig. 5) secured to the inner sides of the legs of the bracket 34 and to opposite sides of the plate member 29, are adapted for bearing engagement with the plate 29 to support the lifting arm 27 against lateral tipping movement relative to its pivotal support 35.

The forward ends of the lifting arms 27 and 27a are secured together by a transverse connecting structure (Figs. 7, 8 and 9) including a transverse pipe member 39 secured at its opposite ends to fastening plates 41. Brace members 42 are connected between the pipe member 39 and the fastening plates 41. In the assembly of the loader the pipe member 39 is extended between the forward ends of the arms 27 and 27a and the fastening plates 41 are secured to the plate members 33 by bolts 43. By virtue of this detachable connection of the pipe member 39 with the lifting arms 27 and 27a, the arms are adapted to be handled separately in their assembly with and removed from the tractor. A scoop 44 is pivotally supported between the arms 27 and 27a, at a position forwardly of the connecting member 39, on pins 46 carried at the front ends of the plate members 33 which are projected forwardly of the lifting arms 27 and 27a.

With the arms 27 and 27a pivotally supported on the bolts 35 at positions spaced upwardly from the tractor rear axle 21, the scoop 44, at its elevated position, is extended forwardly ahead of the tractor a greater distance relative to the distance it would be extended if the members 28

were supported directly on the pivots indicated as 41 in Fig. 1. Thus assuming the lifting arms to be pivoted at 47, the scoop pivots 46, on an upward pivotal movement of the arms would follow an arcuate path indicated in a solid line 5 at A in Fig. 1. However with the lifting arms 27 and 27a pivotally supported at 35 the scoop pivots 46 follow an arcuate path indicated in Fig. 1 by the dotted lines B.

10 As a result, when the scoop 44 is in its elevated position, shown in dotted lines in Fig. 1, it is moved farther ahead of the tractor, by a distance indicated at C, than it would be moved if the lifting arms were pivoted at 47. For a given 15 length of the lifting arms 27 and 27a, therefore, the scoop 44, at its elevated position, is located farther ahead of the tractor by virtue of the pivotal support of the arms at a position spaced upwardly from the main arm members 28.

20 The arms 27 and 27a are raised and lowered by means including a hydraulic power unit, designated generally as 48 (Fig. 4), of a usual type provided as an attachment for John Deere tractors. The unit 48 is supported on the tractor rear axle 21 and includes a transverse rock shaft 49 rotatably supported in a tubular housing 51 extended across the top the rear axle structure 21. Mounted at opposite ends of the rock shaft 49 are a pair of rearwardly extended rocker arms 52 (Figs. 3 and 4). Each arm 52 has formed in a side thereof adjacent its end 53 a V-shape recess 54 adapted to receive a squared end 56 of the shaft 59. With the squared end 56 within the recess 54 a rocker arm 52 is secured in a fixed 30 position on the shaft 49 by a clamping unit 57.

35 The rocking of the shaft 49, and in turn a rocking movement of the rocker arms 52, is accomplished by hydraulically operated means (not shown) formed as a part of the hydraulic power 40 unit 48, and controlled by a pair of foot actuated pedals 72 and 72a which are mounted on a common shaft 73 supported in bearings 74 at the top of the housing 51. The pedal 72 is formed with a rearward extension, which is pivotally connected to the upper end of a rod member 76. The lower end of the rod 76 is pivoted to a valve handle 77.

45 On an initial depression of either one of the 50 foot pedals 72 and 72a the rocker shaft 49 is hydraulically operated to move the rocker arms 52 in a clockwise direction as viewed in Fig. 4. On a release of a foot pedal 72 and 72a the rock shaft 49 is held in a fixed position against movement. When a foot pedal 72 or 72a is depressed 55 a second time the rock shaft 49 is released for free rockable movement. It is seen, therefore, that the rock arms 52 are elevated, held in an elevated position, and then released for lowering by alternately depressing and releasing a foot pedal 60 72 or 72a. Since the operation of the hydraulic power unit 48 is well-known, a further description of its operation is believed to be unnecessary.

65 Cables or chains 58 are connected at one of their ends 59 with the free or rear ends of the 70 rocker arms 52, and from their ends 59 extend downwardly for travel about pulleys 62, and then upwardly for connection of their ends 63 with the plate members 32 at the rear ends of the lifting arms 27 and 27a. The pulleys 62 are rotatably supported in U-shaped brackets 64, arranged at opposite ends of a transverse tractor drawbar 66, which is pivotally supported on bolts 67 carried at the rear end of a supporting structure, indicated generally as 68, and secured at its forward

end 68 to the bottom side of the differential housing 22. Brace members 11 are connected at one end to the upright U members 34, while their opposite ends are supported on the bolts or pivots 67.

On a rocking movement of the rock arms 52, in a clockwise direction, as viewed in Fig. 1, the cables or lifting members 58 provide for the application of a pulling force in a downward direction at the rear ends of the lifting arms 27 and 27a whereby the arms are pivotally moved to raise the scoop 44 to an elevated position shown in dotted lines in Fig. 1. The scoop 44 is held in an elevated position when the power unit 48 is operated to hold the rocker arms 52 against movement. When the cables 58 are released by releasing the rocker arms 52 for free rockable movement, the scoop 44 is movable to a lowered position by the action of gravity, whereby the rocker arms 52 are moved by the cable in a counter-clockwise direction, as also viewed in Fig. 1.

Because the lifting arms 27 and 27a are projected rearwardly from their pivotal supports 35 the leverage effect of the lifting arm lengths between their rear ends and the pivotal supports 35 is fully utilized in raising the load carried by the scoop 44. It is further apparent that the weight of the lifting arms 27 and 27a, located rearwardly of the arm supports 35, acts to counter-balance a part of the weight of the arms located forwardly of the pivots 35. The arms 27 and 27a may be completely balanced, relative to their fulcrum or pivot 35 by securing suitable weights to the rear ends of the arms. Since any weight of the lifting arms or any weights secured to the lifting arms, rearwardly of the pivots 35, counter-balances any weight carried on the arms forwardly of the pivots 35, the power required to elevate the scoop is reduced in proportion to the balanced condition of the lifting arms.

The latch mechanism for holding the scoop 44 in a load carrying position includes a rock shaft 81 (Figs. 2, 7, 8 and 9) rotatably supported in a pipe member 80 welded to the top side of the connecting member 39. The inner end of the rock shaft 81 is integrally formed with an upright latch member 82 adapted to releasably engage a catch member 83 projected rearwardly from the back wall 84 of the scoop 44. The catch 83 consists of a bolt extended through the opposite legs 86 and 87 of an upright channel member 88 which is adjustably supported on the scoop back wall 84 by bolts 89 carried in the back wall 84 and extended through slots 91 formed in the base side of the channel member 88, which base side is positioned flat against the back wall 84 so that the channel is open to the latch member 82. Adjustment of the channel member 88 relative to the scoop back wall 84 provides for an adjustment of the suction or digging action of the scoop during a bucking operation.

As best appears in Figs. 2 and 7 the leg 86 of the channel member 88 has a downward extension 92, the lower edge of which is adapted for abutting engagement against the top side of the transverse connecting member 39. On a return of the scoop 44 from a dumping position to a loading position, the abutting engagement of the extension 92 with the connecting member 39 limits the pivotal movement of the scoop in a counter-clockwise direction, as viewed in Fig. 1, at which limiting position the latch member 82 is releasably engageable with the catch member 83.

The outer end of the rock shaft 81 is integrally

formed with an upright rock arm 93 the free end of which is connected to the rear end of a coil spring 94. The forward end of the spring is secured at 96 to the top side of the brace member 31. The spring 94 thus acts to yieldably move the rock shaft 81 in a clockwise direction, as viewed in Fig. 7, to in turn provide for the movement of the latch member 82 into an engaging position with the catch member 83.

10 The latch member 82 is released from its engaged position with the catch member 83 on actuation of a rod member 98 extended longitudinally of the brace member 31 of the lifting arm 27, and slidably supported in upright projections 99 on the top side of the brace member 31 (Fig. 1). The rear end of the rod 98 is formed with a handle 101 located adjacent to the seat 102 for the tractor operator. The forward end of the rod 98 (Fig. 7) is formed with a loop 103 which is extended through the free end of the rocker arm 90.

When the rod 98 is pulled in a rearward direction, the rock shaft 81 is moved in a counter-clockwise direction, as viewed in Fig. 7, against the action of the spring 94, whereby the latch member 82 is moved out of engagement with the catch member 83. On a release of the rod member 98 the catch member 82 is moved into an engaging position with the catch member 83 by the spring 94.

30 The return of the scoop 44 from a dumping position to a load carrying position is accomplished by the action of gravity. In other words the weight of the scoop located rearwardly of the scoop pivots 46 is greater than the weight of the scoop located forwardly of the pivots 46. However, when the scoop is loaded the forward portion of the scoop overbalances the rear portion of the scoop so that on a release of the catch member 82, the scoop is moved by gravity to a dumping position. After the load is dumped, the greater weight of the scoop is rearwardly of the pivots 46, whereby the scoop is pivotally moved by gravity in a counter-clockwise direction, as viewed in Fig. 7, to its normal load carrying position.

As previously mentioned the connecting member 39 is detachably connected between the forward ends of the lifting arms 27 and 27a to provide for the independent handling of the lifting arms for assembly with and removal from the tractor. As clearly appears in Fig. 8 the rocker arm 81 is pre-assembled as a unit with the connecting member 39, and is removable from the loader with the member 39, by merely disconnecting the rod 98 and the spring 94 from the rock arm 93.

In Figs. 10-14, inclusive, there is shown a modified form of the invention which is similar in all respects to the loader attachment illustrated in Fig. 1, except that the lifting arms 27 and 27a are mechanically operated from the power take-off shaft 23, instead of by the hydraulic power unit 48. Similar numerals of reference, therefore, are used in Figs. 10-14, inclusive, to designate like parts in Fig. 1.

The mechanical means for operating the lifting arms 27 and 27a includes a base member 101 (Figs. 10, 11 and 12) secured to the drawbar 66 by U-clamps 102 and extended longitudinally of the tractor. The forward end of the base 101 is integrally formed with an upright open rectangular frame 103 positioned adjacent to the differential housing 23. A longitudinal shaft 104 is rotatably supported in bearings 105, carried on

the base 101, has its front end projected through the rear side of the rectangular frame 103.

A hollow brake drum 107, mounted on the front end of the shaft 104, is rotatable within and transversely of the rectangular frame 103. Cables 108 have one of their ends windable about the shaft 104, between the bearings 106, and from the shaft travel about pulleys 109, mounted on the drawbar 66, and then extended upwardly for connection of their opposite ends 111 with the plate members 32 at the rear ends of the lifting arms 27 and 27a.

Thus on rotation of the shaft 104 in one direction the cables are wound thereon, whereby a scoop lifting force is applied downwardly on the rear ends of the lifting arms 27 and 27a. When the shaft 104 is held against rotation the scoop 44 is maintained fixed in an elevated position. On release of the shaft 104 from its held position, the scoop 44 is lowered by gravity and the cables 108 are unwound from the shaft 104 by the downward pivotal movement of the lifting arms 27 and 27a.

Rotation of the shaft 104, to wind the cables 108 thereon, is accomplished by the connection of the shaft 104 with the power take-off shaft 23 through a friction clutch unit which includes the hollow brake drum 107 (Figs. 12 and 14). The power take-off shaft 23 extends through an upright elongated opening 112 formed in the front side of the rectangular frame 103. Mounted on the power take-off shaft 23, and located within the hollow brake drum 107, is an inflatable rubber tire 113.

The clutch unit is illustrated in Figs. 12 and 14 in its disconnected position, in which the tire 113 is freely rotatable within the brake drum 107. On movement of the brake drum 107 downwardly, so that its inner peripheral surface is in frictional engagement with the outer peripheral surface of the tire 113, the shaft 104 is connected by the clutch unit in a driven relation with the power take-off shaft 23. Downward movement of the brake drum is provided by virtue of the pivotal support of the drawbar 66 on the pivot bolts 67.

Actuation of the clutch unit is accomplished by means including a manually operated upright lever 114 pivoted at 116 (Figs. 11 and 12) on a bracket 117 secured to and extended rearwardly from the differential housing 22. Brace members 118 and 119 are connected between the free ends of the bracket 117 and the housing 22. An upright projection 121 at the front end of the rectangular frame 103 is pivotally connected at 122 with the lever 114 at a position above the pivot 116.

When the lever 114 is moved forwardly, or pivoted in a counter-clockwise direction as viewed in Fig. 12, the entire base 101 and the frame 103 are pivoted downwardly and forwardly whereby the brake drum 107 is moved into frictional engagement with the rubber tire 113. On a rearward movement of the lever 114 the brake drum is lifted out of frictional engagement with the tire.

To hold the drum 107, and in turn the shaft 104, against rotation there is provided a brake band 124 (Figs. 11, 13 and 14) which is extended about the outer periphery of the drum 107. One end 126 of the band 124 is of a looped form adapted for connection with a bent bolt 127 carried in the top side of the rectangular frame 103. The opposite end 128 of the brake band 124 is bent upright and loosely receives a bolt 129 extended laterally from the top side of the rectangu-

lar frame 103 at a position oppositely arranged from the bent bolt 127. As best appears in Fig. 13, the band end 128 projects upwardly above the top level of the rectangular frame 103. A coil spring 131, mounted about the bolt 129, is arranged in compression between the band end 128 and a nut 132 at the free end of the bolt 129.

Movably supported in a spaced relation above the top side of the rectangular frame 103 is a cam bar 133 (Figs. 11, 12, 13 and 14) having a low spot 134 formed intermediate its ends and in one side thereof. The cam bar is extended longitudinally of the base 101 and has its front end pivoted at 136 to the lower end of the operating lever 114. The rear end of the cam bar is guidably movable between a pair of spaced upright lugs 135 on the top side and at the rear end of the rectangular frame 103. The bar 133 has an elongated opening 137 for slidably receiving a bolt 138 carried between the lugs 135.

The cam bar is yieldably engageable with a lateral projection or cam follower 139 provided on the brake band end 128, and adapted to ride into and out of the cam low spot 134 on longitudinal movement of the cam bar 133. The yieldable engagement of the cam bar with the cam follower 139 is maintained by the spring 131. When the follower 139 is within the low spot 134, the spring 131 is capable of holding the brake band 124 in frictional engagement with the brake drum 107, to hold the drum against rotation. When the low spot 134 is moved to either side of the cam follower 139 the spring 131 is compressed so as to release the brake band 124 from frictional engagement with the brake drum 107.

In the operation of the modified form of the invention assume the lifting arms 27 and 27a to be in their lowered positions, shown in Fig. 10, and the clutch unit to be in its disconnected position shown in Figs. 11 and 13, in which the tire 113 is freely rotatable within the brake drum 107, and the cam follower 139 is within the cam low spot 134. The shaft 104 is thus out of a driven relation with the power take-off shaft 23, and the brake band 124 is held in frictional engagement about the brake drum 107 by the spring 131.

To elevate the scoop 44 the operating lever 114 is pivotally moved in counterclockwise direction, as viewed in Fig. 12, whereby the brake drum 107 is moved downwardly into frictional engagement with the tire 113 to connect the shaft 104 with the power take-off shaft 23. Concurrently with this downward movement of the brake drum 107 the cam bar 133 is moved to the right, as viewed in Fig. 11, whereby the cam low spot 134 is moved away from the cam follower 139. By virtue of this movement of the cam bar 133 the brake band end 128 is moved toward the right, as viewed in Fig. 13, to release the brake band from its engaged position with the brake drum 107. The scoop is held in an elevated position by the return of the lever 114 to its position shown in Fig. 12, to provide for the upward movement of the brake drum 107 out of frictional engagement with the tire 113, and for the movement of the cam low spot 134 to a position for receiving the cam follower 139. With the cam follower 139 in the cam low spot 134 the brake band 124 is moved by the spring 131 into frictional engagement with the brake drum 107 whereby the shaft 104 is held in a fixed position.

To lower the scoop 44 the operating lever 114 is pivotally moved in a clockwise direction, from 75 its position shown in Fig. 12. This movement of

the operating lever 114 moves the brake drum 107 upwardly away from a frictionally engaging position with the tire 113, concurrently with the movement of the cam bar 133 toward the left, as viewed in Fig. 11, whereby the cam low spot 134 is moved away from the cam follower 139. The shaft 104 is thus maintained out of a driven relation with the power take-off shaft 23, while the brake band 124 is moved out of frictional engagement with the brake drum 107, to provide for a free lowering of the scoop 44 by the action of gravity. On a downward movement of the scoop 44 the cables 108 are unwound from the shaft 104.

It is seen, therefore, that the single lever 114 operates both the clutch unit for connecting and disconnecting the power take-off shaft 23 with the shaft 104, and the brake mechanism for holding the shaft 104 in a fixed position against rotation, in a timed relation so that the shaft 104 is capable of free rotation when it is connected with the power take-off shaft 23 and when it is desired to lower the scoop 44.

From a consideration of the above description it is seen that the invention provides a loader attachment for a tractor which is of a simple and rugged construction and comprised of a minimum number of parts which are capable of being separately handled by one man in their assembly and removal from the tractor. The operating means, for raising and lowering the pivoted arms 27 and 27a, are located rearwardly of the tractor axle 21 so as to be out of the normal line of vision of the tractor operator. Further, the pivoted lifting arms, as well as the operating means therefor, are arranged entirely within the vertical and transverse confines of the tractor, so as not to interfere in any way with the usual storage of the tractor in a machine shed or the like.

Although the invention has been described with respect to several embodiments thereof, it is to be understood that it is not so limited since changes and modifications can be made therein which are within the full intended scope of this invention as defined by the appended claims.

I claim:

1. A loader attachment for a tractor having a rear axle, including a pair of pivoted lifting arms arranged at opposite sides of said tractor, a load carrying unit supported between the forward ends of said arms, upright members on said arms intermediate the ends thereof, a pair of upright supports oppositely arranged on said axle, means pivoting said upright members on said upright supports for up and down pivotal movement, means on said upright supports guidably engageable with said upright members to hold said arms against lateral movement at any pivotally moved position therefor, and power operated means adapted to act on the rear ends of said arms to pivotally move said arms to raise and lower said load carrying unit.

2. A loader attachment for a tractor having a rear axle and a transverse draw bar, including a pair of pivotal lifting arms arranged at opposite sides of the tractor, means pivotally supporting said lifting arms on said axle intermediate their ends for pivotal up and down movement, a scoop carried between the front ends of said lifting arms, means for raising and lowering said lifting arms including a transverse rock shaft supported on said rear axle, a pair of rearwardly extended rock arms mounted on said rock shaft, a pair of pulleys, means supporting said pulleys on said draw

bar at oppositely arranged positions, a pair of flexible means connected at one of their ends to the rear ends of said lifting arms, and extended downwardly about said pulleys for connection of their opposite ends with the free ends of said rock arms, and means operated by the tractor for rocking said rock shaft.

3. A loader machine including a portable frame, a pair of pivoted lifting arms arranged at opposite sides of said frame, means pivotally supporting said arms on said frame for up and down pivotal movement, a scoop pivoted between the forward ends of said arms, a transverse member connected between said forward ends, a transverse rock shaft supported on said connecting member, a latch member on said rock shaft, a catch member adapted for releasable engagement with said latch member, means adjustably supporting the catch member on said scoop for up and down movement, a stop member on said adjustable means adapted to engage said connecting member to limit pivotal movement of said scoop in one direction, means acting in one direction on said rock shaft to yieldably retain said latch member in an engaging position with said catch member, and manually operated means for rocking said rock shaft in an opposite direction to release said latch member from said catch member.
4. A loader attachment for a tractor having a rear axle comprising, a pair of pivoted lift arms arranged at opposite sides of said tractor, with the front ends of said arms being extended forwardly of said tractor and the rear ends of said arms projected rearwardly of said axle, means for pivotally supporting said arms at positions above said axle including pairs of upright transversely spaced supports on said axle for receiving said arms therebetween, upright members on said arms, pivots carried in said spaced supports and extended through said upright members, and bearing members on said spaced supports engageable with opposite sides of said upright members to guide said arms against movement transversely of the tractor.
5. A loader attachment for a tractor having a rear axle comprising, a pair of pivoted lift arms arranged at opposite sides of the tractor, with the front ends of said arms being extended forwardly of the tractor and the rear ends of said arms projected rearwardly of said axle, means for pivotally supporting said arms at positions above said axle including pairs of upright transversely spaced supports on said axle for receiving said arms therebetween, and coating means on said arms and supports for guiding said arms against movement transversely of said tractor.

60 JOS. B. KUCERA.
